UNITED STATES PATENT OFFICE.

BRUCE C. HEATH, OF LOUISVILLE, KENTUCKY.

EYE-CUP.

1,244,498.

Specification of Letters Patent. Patented Oct. 30, 1917.

Application filed May 14, 1917. Serial No. 168,360.

To all whom it may concern:

Be it known that I, BRUCE CROMWELL HEATH, a citizen of the United States, residing in the city of Louisville, county of Jefferson, and State of Kentucky, have invented a new and useful Improvement in Eye-Cups, of which the following is a specification.

This invention relates to eye cups.

Eye cups, usually made of glass, the rim of which is contoured to fit about an eye, and having a depending stem and base, by which they are upheld, are well known, but not as generally used as they should be, owing to the inconvenience attending their use. It being necessary, after the placing of a fluid in the cup, to lean forward, thus bringing the face into a horizontal plane, before adjusting the cup to the eye, to avoid spilling the liquid. Then to lean backward until the face assumes a horizontal position thus inverting the cup and bringing the fluid into contact with the eye, laving being accomplished by opening and closing the eye lid.

Any fluid that may escape from under the edge of the cup, trickles down the face and on to the clothing. A further objection to the use of the conventional eye cup, is that any detritus, or infectious matter that may be loosened by the laving is not carried out of, and away from the eye, but remains suspended in the lavage fluid within the eye, and is even carried thereby to other points as yet uninfected.

An object of this invention is to provide an eye cup with which the eye may be bathed without moving the head to an abnormal position.

A further object is to provide an eye cup that is sanitary inasmuch as that foreign, or infectious material will be removed from the eye by the fluid applied thereto, which will not again come in contact therewith, fresh fluid only coming in touch with the eye.

With the foregoing and other objects in view, the invention consists of the novel construction and arrangement of parts illustrated in the accompanying drawing, which forms a part of this specification, wherein is set forth an embodiment of the invention, but it is to be understood that such changes and modifications may be resorted to as come within the scope of the appended claims.

Referring now to the drawing, wherein similar reference characters designate like parts in the several views, Figure 1, is a central vertical longitudinal section of an eye cup, constructed in accordance with my invention, an attached removable compressible bulb being shown in elevation: Fig. 2, a central transverse section of Fig. 1: Figs. 3 and 4, are central longitudinal sectional views of modified forms of my invention and Fig. 5, a detail in elevation.

In the drawing the reference numeral —1— designates a cup or bowl, of conventional, or suitable design, the brim of which is so shaped as to conform to the contour of the eye, and which may be formed of any suitable material such as rubber, aluminum, or glass. From a suitable point on the periphery of the cup, preferably the lower portion thereof, there is extended suitable means, such as a nipple —2— for the attachment thereto of suitable means, such as a compressible rubber bulb —3— whereby a current of fluid may be projected through a passage —4— into the interior of the cup. This passage extends through the nipple and follows the contour of the cup, preferably at one end thereof, being formed in the body of the cup, and extends to within a spaced distance of the top thereof. An abutment —5— positioned on the body of the cup opposite the outlet of the passage serves to deflect the issuing fluid. A wall of the cup is provided with an aperture —6— which is surrounded on the inner side by a raised portion —7— which prevents circulating liquid from escaping therethrough. The aperture is positioned on or near the level of the upper end of the passage 4. The bulb is preferably provided with a flat bottom in order that it may serve as a base to uphold the cup. The mode of use is as follows: A quantity of fluid, medicated if desired, is placed in the bulb. The quantity of fluid placed in the bulb should be such that when forced into the cup it will not come up to the outlet of the passage 4. The user then leans forward and adjusts the cup to the eye, with the outlet of the passage 4 near the outer corner of the eye, pressure is then exerted on the bulb, forcing the fluid therein through the passage. As the fluid leaves the passage it impinges upon, and is deflected by the abutment 5 so that it strikes the eye at the outer canthus at such an angle that it sweeps across the surface, loosening and carrying

with it any foreign substance, the force of the stream depending upon the pressure applied to the bulb, and emerging at the inner canthus, whence it falls to the bottom of the cup. It will be observed that fresh fluid only contacts with the eye, that used fluid, which may have infectious matter in suspension, is not again brought into contact with the eye, consequently there is no danger of carrying infection to uninfected portions by the use of this improved eye cup. In Fig. 3, I have shown a modified construction wherein instead of forming a passage in the body of the cup, a tube —10— is employed, it being bent to conform to the contour of the cup, and the lower end of the tube being fitted into a passage —11—, which extends through the nipple 2, where it may be secured by suitable means such as cementing. The tube 10, conforms to the contour of and lies along the inner surface of an end of the cup, extending to within a spaced distance of the upper edge thereof. The upper end of the tube 10 is provided with a wing —14— which serves to deflect issuing fluid so that it will impinge upon the eye at a suitable angle. A straight tube —12— may be used, in which case it will stand erect in the cup and extend to within a spaced distance of the top thereof, in this case issuing fluid will contact with the eye near the center thereof and flow in each direction thereover, the used fluid accumulating in the cup below the top of the tube. While cementing has been mentioned as a means of securing the tubes in position, it is to be understood that they

may be held frictionally within the passage 16 in which case they may be removed for the purpose of cleansing the cup.

From the foregoing description it will be seen that I have provided an eye cup convenient to use and which is efficient and sanitary in service.

Having thus described my invention so that any one skilled in the art pertaining thereto may make and use the same, I claim:

1. A cup adapted to be applied to an eye, comprising a bowl, a nipple extended from the surface thereof and having a passage leading therethrough into the interior of the cup and a tube removably positioned in said passage and extending through the cup to within a spaced distance of the brim thereof.

2. A cup adapted to be applied to an eye, comprising a bowl, a nipple extended from the surface thereof and having a passage leading therethrough into the interior of the cup, and a tube removably positioned in said passage, said tube being bent to conform to and extending along the inner surface of the cup to within a spaced distance of the brim.

3. An eye cup, a nipple extended from the surface thereof and having a passage leading therethrough into the interior of the cup, a tube removably seated in said passage, said tube being bent to conform to and extending along the side of the cup to within a spaced distance of the brim, and a wing on the end of said tube adapted to deflect issuing fluid.

BRUCE C. HEATH.
